CLAIM

The ornamental design for a contour follower for a fluid jet cutting machine, substantially as shown and described.

DESCRIPTION

FIG. 1 is a top isometric view of a contour follower for a fluid jet cutting machine.

FIG. 2 is a bottom isometric view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof; and,

FIG. 8 is a bottom plan view thereof.

Stippling shown in the drawings provides surface shading and is not intended to indicate surface decoration. The broken lines in the drawings depict unclaimed environmental subject matter.
